UNITED STATES PATENT OFFICE.

EDWARD H. STEARNS, OF ERIE, PENNSYLVANIA.

IMPROVEMENT IN EDGING-MACHINES.

Specification forming part of Letters Patent No. 143,264, dated September 30, 1873; application filed December 30, 1872.

To all whom it may concern:

Be it known that I, EDWARD H. STEARNS, of Erie, in the county of Erie and State of Pennsylvania, have invented a new and useful Improvement in Edging Machine; and I do hereby declare the following to be a full, clear, and exact description thereof, reference being had to the accompanying drawing making part of this specification, in which—

Figure 1 represents a perspective view of my improved machine. Fig. 2 is a top or plan view thereof. Fig. 3 is a sectional view through $x x$, Fig. 2; and Fig. 4 is a like section, just inside the rack and pinion.

Like letters of reference indicate like parts in each.

My invention relates to a machine for edging and slitting boards. All or nearly all machines of this class have a feed-table, a side rail for a gage, one or more movable or fixed saws on a mandrel, and one or more pairs of pressure-rollers. My present invention consists of improvements in the feed devices, both those in front and those in the rear of the saws, and in the guide or gage devices employed in feeding, substantially as hereinafter described.

To enable others skilled in the art to make and use my improvement, I will proceed to describe its construction and mode of operation.

The frame A of the machine is of the usual construction. The side or gage rail B, the rest-rollers B¹, the saw-mandrel D, and the saws D¹ (the latter in any desired number, and some or all movable or fixed at pleasure,) are such as are common in machines of this class, and need not be more fully described. The rolls H H¹ are pressure-rolls, arranged in the rear of the saws (or in front, if so preferred,) for carrying the lumber along to, or delivering it from, the saw. The first part of my invention relates to these rollers. The lower roll H¹ has fixed bearings, and, preferably, a positive motion, as shown. The upper roll H is movable up and down by a parallel motion, so as to provide for the passing through of boards of different thicknesses. It consists of an outer or roll part a, Fig. 3, which is provided with a band wheel or pulley, a¹, and both are slipped like a sleeve onto the shaft

a², so as to have a rotary motion on, and independent of, the shaft. A pinion, r, is secured to each end of the shaft a². These pinions mesh into the curved tooth-rack c¹ of the uprights c². These uprights are slotted, as shown. The slots and racks are curved, with a radius of curvature corresponding to the length of the band b, by which the roll receives its motion. One end of the shaft a² extends out sufficiently far to make connection with an arm, f, from the lever f¹, which extends back to within convenient reach of the operator. The periphery of the roll H has serrations of the form of ratchet-teeth, as shown in Fig. 3, the edges or acute angles of these being forward in the direction of the motion, so as to catch upon the end of a thick plank and rise onto it without any aid from the operator; but when additional aid is required, the operator, by working the lever f¹, can raise or lower the roller H at pleasure. This motion is communicated directly to the shaft a² and the pinions r. These pinions mesh into the curved racks c¹, and move up and down with a uniform motion. Hence, both ends of the roller H will always be at the same distance from the lower roll, and will consequently bear evenly along the entire width of the board, and thereby secure uniformity of feed. The roller hence performs its function of a feed-roller, even when changing its position in a vertical direction.

The next part of my invention relates to a sectional rest-roll, P, which is used, preferably, without any pressure-roll, and is designed to guide the lumber in a direct line forward as it passes from the saw. The tendency of the board sometimes is to swerve laterally, so that the saw shall follow the grain of the wood. To prevent this, and insure a feed directly forward, toothed rollers have been tried, but with poor success, as the teeth entered the face of the board to such depth as to injure the face of the dressed board. As a substitute for such toothed rollers, I have devised a roller, P, with a series of short, sharp spurs, s s, at various points along its length. These spurs are sharp enough to catch the strips into which the board is cut, and prevent their swerving from a direct line forward, but are so short that they will not

enter the board to such depth as to cause injury. They may be made on the face of a solid roll, or the roll may consist of a series of rings, p , provided with spurs s , such rings being slipped onto a common shaft, so as to be capable each of an independent motion. This latter is the preferable construction. Then, if two operators are at work on different sides of the machine, the sections p at the opposite ends of the roller P may work independently of each other. While the rear end of one board is resting on a part of the sections p , so as to prevent them from revolving, another board may be passing along over the other sections, which will rotate freely.

I have also devised an adjustable side or gage rail, shown at R , to be used as a guide in feeding. Such guides have been made adjustable by means of pins therefrom extending down through slots, and they were held in place at the desired point of adjustment by nuts or set-screws. But, for every different width to be sawed off the edge, the operation of sawing must be stopped till the adjustment is changed. To overcome this difficulty I attach to the feed-table the plates d d , each having a series of inclined slots, e e , connected together by a series of slots, e' e' , which run in the direction of the feed motion. The gage-rail R is movable. It has pins, as indicated by dotted lines at r' r' , which play in the slots e e' . The operator, knowing the breadth of edge he wishes to cut from the board, sets the guide-rail R , with its pins, r' , in the proper slot e' . To set it for cutting off another breadth of edge, he slips the rail, with its pins passing along the inclined slots e , in or out, as he may desire, till the pins r' r' come in the proper slot e' , and then the work proceeds. The pins, when in any of the slots e' , will keep their place till shifted by the operator to another slot. In connection with the guide-rails it is desirable to use some device which, after the forward end of the board has passed between the feed-rollers, and while it is being fed forward thereby, will hold its edge fair and true against such guide-rail, and thereby relieve the operator to that extent. For this purpose I employ the wheels or rollers n , which are made with short, sharp spurs s' , similar to those, s , already described. These wheels or rollers n I mount on horizontal shafts or stems n' , whose axes incline a little forward, so that, as the board advances, the

spurs s' , engaging its under surface, will, by the direction of their movement, while thus engaging the surface, tend to press the board over against the guide-rail, and thus automatically hold it in place. The operator then, after entering one board, is free to get another ready while the former one is passing through the machine. The spurs s s' may be made either on the face of cylindrical rings, or they may be cut out like small saw-teeth on the edge of a circular sheet-metal plate, of the proper diameter, and such plate be slipped onto the stem or shaft, and held in place by nuts and washers, in the usual way. The latter mode of making them, on account of its cheapness, and the facility with which the spurs can be renewed, is probably preferable.

What I claim as my invention, and desire to secure by Letters Patent, is—

1. As a means for securing a parallel motion in the movable roll of a pair of feed-rolls, a pinion on each end of such roll, meshing each into a curved-toothed rack, substantially as set forth.

2. The movable feed-roll H , consisting of a shaft by means of which the roll is moved vertically, and a roller part, a , with its pinion or band wheel, a' , slipped onto the shaft, so as to have a fixed positive rotary motion, independent of the shaft, and at all points of the vertical travel of the shaft, substantially as set forth.

3. The sectional roll P , in combination with pressure-rolls H H' , substantially as and for the purposes set forth.

4. In a machine for edging or slitting boards, the combination of a side guide or rail, fixed or adjustable, and a spurred guiding-roller, n , arranged with its axis at an acute angle to the direction of the feed, substantially as and for the purposes described.

5. As a device by which to set an adjustable guide-rail, a series of slots, e' , running in the direction of the feed, two or more in number, when connected with each other by an inclined slot or slots, substantially as set forth.

In testimony whereof I, the said EDWARD H. STEARNS, have hereunto set my hand.

EDWARD H. STEARNS.
